UNITED STATES PATENT OFFICE.

LOUIS FRIEDMAN, OF NEW YORK, N. Y.

DESIGN FOR A NECKTIE.

Application filed December 15, 1923. Serial No. 8,048. Term of patent 7 years.

To all whom it may concern:

Be it known that I, LOUIS FRIEDMAN, a citizen of the United States, residing at New York, in the county of New York and State of New York, have invented a new, original, and ornamental Design for a Necktie, of which the following is a specification, reference being had to the accompanying drawing, forming part thereof.

The figure is a perspective view of a necktie, showing my new design.

I claim:

The ornamental design for a necktie, as shown.

In testimony whereof I have affixed my signature this 10th day of December, 1923.

LOUIS FRIEDMAN.
